COMBINED LUGGAGE CARRIER AND BOAT

William D. Harmsen, Wheat Ridge, Colo., assignor to Jolly Rancher Sales Company, Wheat Ridge, Colo., a corporation of Colorado

Filed Oct. 27, 1961, Ser. No. 67,280

Term of patent 14 years

(Cl. D14—27)

The dominant features of my design for a combined luggage carrier and boat reside in the portions thereof shown in full lines, the car roof and luggage rack shown in broken lines in FIG. 1 being for illustrative purposes only.

I claim:

The ornamental design for a combined luggage carrier and boat, as shown and described.
